UNITED STATES PATENT OFFICE.

WILLIAM A. MCGUIRE AND ELMER E. COOK, OF CHICAGO, ILLINOIS, ASSIGNORS
TO THE MCGUIRE MANUFACTURING COMPANY, OF SAME PLACE.

COMBINED SNOW PLOW AND SWEEPER.

SPECIFICATION forming part of Letters Patent No. 669,761, dated March 12, 1901.

Application filed November 17, 1899. Serial No. 737,331. (No model.)

To all whom it may concern:

Be it known that we, WILLIAM A. MCGUIRE and ELMER E. COOK, citizens of the United States, residing at Chicago, in the county of 5 Cook and State of Illinois, have invented certain new and useful Improvements in a Combined Snow Plow and Sweeper, of which the following is a specification, reference being had to the accompanying drawings.

10 Our invention relates to combined snow plow and sweeper cars especially adapted for use in street-railways, and particularly that class of cars in which rotary brushes driven by suitable power are located below the car 15 for the purpose of sweeping the tracks clear of snow. Heretofore in cars of this class it has been the custom to mount the brooms, and particularly brooms in the form of rotary brushes driven by suitable power, below 20 the car, with their axles in a line diagonal to the track, in order that the snow may be swept forward and to one side as the car moves. In order to properly support such brushes, it is necessary that they should be 25 carried under the body of the car or under the platform, and one difficulty which has arisen in the use of these cars lies in the fact that the snow, which is thrown diagonally forward and to one side by the brush, strikes 30 the base of the car and is not thrown clear of the track.

It is one object of our invention to provide a sweeper-car which shall do away with these difficulties by means of constructing the car 35 with its base or support provided with diagonal or angular ends which extend across the car from side to side and to support immediately beneath the diagonal ends of the car brushes which are so placed with relation to 40 the diagonal ends of the car-base that they are supported by the car-base and at the same time will throw the snow clear of the bottom of the car, so as not to be caught thereby and thrown back upon the track.

45 It is another object of our invention to provide a car having a base or body so formed with brushes located at each end thereof capable of sweeping the entire width of the track and so located with reference to the car- 50 body as to throw the snow clear of the track.

In the drawings, Figure 1 is a side eleva-

tion of the car. Fig. 2 is a top or plan view of the bottom of the car seen from above. Fig. 3 is an enlarged detail, being a side elevation of one end of the car. Fig. 4 is an enlarged detail, being a top or plan view of one end of the bottom of the car with top and sides removed, the bottom being partially cut away to show the mounting of the brushes. Fig. 5 is an enlarged detail, being a front view of the broom-axle and means of mounting the same. Fig. 6 is an enlarged detail, being a side view of one of the brush-hangers; and Fig. 7 is an enlarged detail, being a vertical section on line 7-7 of Fig. 4. 65

Referring to the drawings, 11 indicates the body of a car, mounted upon a base 12. At each end the base 12 is carried out into platforms 13, the outer edge of which is diagonal to a line running longitudinally of the car, as 70 is best shown in Figs. 2 and 4.

14 indicates rotary brushes which are mounted upon axles 15 (see Fig. 5) below the car. The axles 15, mounted as hereinafter described, extend across the car from side to 75 side diagonally of a line longitudinally of the car and of the track and parallel with the front edge of the platforms 13 and at such a distance behind the platforms that the outer surface of the brushes 14 will extend almost 80 out to a line dropped vertically from the outer edge of the platforms 13. When the brushes are rotated to sweep the snow as the car passes along a track, the snow thrown outward and forward will be clear of the car by reason of 85 the relation of the position of the brushes to the platforms.

16 indicates a sprocket-wheel which is keyed or otherwise secured to the axle 15 for the purpose of connecting the same with the 90 driving-shaft, hereinafter described.

17 indicates hangers which are secured to the bottom of the car, the construction being best shown in Fig. 6. The hangers 17 consist of a bracket 18 and of a curved link 19, which 95 is secured to the bracket 18 by bolts 20, so that upon the removal of either of the bolts the link 19 may be swung outwardly from the bracket to permit the insertion of the brush, as hereinafter described. When the link is 100 secured in place, a slot 21 is formed by the bracket 18 and the link 19, which is curved

in the arc of a circle whose radius is the distance between the central longitudinal line of the said slot and the axis of the driving-shaft hereinafter described.

5 22 indicates a brace one end of which is secured to the bracket 18 and the other to the bottom of the car.

23 indicates a block which is adapted to enter the slot 21 and slide freely therein and 10 is provided with a journal in which the axle 15 rotates.

24 indicates lugs which are journaled upon the axle 15.

15 25 indicates chains which are secured at one end of the lugs 24, pass over sheaves 26, and are fastened at their other ends to a shaft 27 below the bottom of the car, which is journaled at its upper end to the bottom of the car and at its lower in a block 28, which is 20 supported by a brace 29.

30 26 indicates a gear which is keyed or otherwise secured upon the shaft 27 and meshes with a gear 31. The gear 31 is keyed or otherwise secured to the lower end of a shaft 32, 25 which extends vertically through the base of the car.

33 indicates a block in which the shaft 32 is journaled.

34 indicates a ratchet-wheel which is keyed 30 or otherwise secured to the shaft 32.

35 indicates a pawl which is pivoted on the upper surface of the block 33 and is adapted to engage the ratchet-wheel 34.

36 indicates a collar which is keyed or otherwise secured to the shaft 32 and operates 35 to hold the ratchet 34 upon the shaft 32 and prevent longitudinal movement thereof, so that the shaft 32 is supported on the block 33.

37 indicates a brace through the upper end 40 of which the shaft 32 passes.

38 indicates a hand-wheel which is fastened on the upper end of the shaft 32. When the shaft 32 is rotated by the hand-wheel 38 in the proper direction, the chains 25 are wound 45 upon the shaft 27, and the axle 15, carrying the brushes, is lifted to any required position and held by the engagement of the pawl 35 with the ratchet 34. When it is desired to lower the brushes, the pawl 34 is disengaged 50 in the usual way, permitting the rotation of the shafts 32 and 27, and the brushes drop by their own weight, the blocks 23 sliding in the slots 21.

39 indicates a driving-shaft which is journaled in suitable bearings 40 above the floor 55 of the car and extends diagonally across the car parallel with the brush-axes 15 and is driven by any appropriate mechanism in the car, which may be connected, for instance, 60 with the sprocket-wheel 41, secured to the driving-shaft 39.

42 43 indicate sprocket-wheels which are

rotatably mounted upon the shaft 29 and are connected by means of sprocket-chains 44 with the sprocket-wheels 16 upon the brush- 65 axle 15, passing through suitable openings 45 in the floor of the car. In Fig. 4 only one of these chains is shown in place, the other being removed for convenience of illustration.

46 (see Fig. 2) indicates hoods or casings of 70 ordinary construction to protect the sprocket-wheels 42 43 and the sprocket-chains 44.

47 indicates a hood or casing of ordinary construction to protect the sprocket-wheel 41.

48 and 49 indicate clutch members which 75 are feathered upon the shaft 39, so as to slide to and fro thereon, and are adapted to engage with corresponding clutch members 50 and 51 upon the sprocket-wheels 42 and 43, respectively.

52 and 53 indicate levers which are pivoted upon supports 54 and 55 and engage with the clutch members 48 and 49, respectively. By the moving of the levers the clutches are thrown into and out of engagement, so that 85 either one or both of the sprocket-wheels 42 43 may be engaged and rotated by the rotation of the driving-shaft 39. In ordinary practice only one will be used, driving the broom at the forward end of the car, according to the direction in which the car is running, the other being thrown out of operation, though it is obvious that the other broom may be rotated to assist in the work if necessary.

That which we claim as our invention, and 95 desire to secure by Letters Patent, is—

1. In a sweeper-car, the combination with a car-base having a diagonal end extending across the car-body from side to side thereof in a rectilinear diagonal line, of a rotary brush 100 adapted to sweep the entire width of the car-track and journaled below said car-base diagonally of the car, the outer periphery of said brush lying in the same vertical plane with the diagonal end of the car-body, and means 105 for driving said brush, substantially as described.

2. In a sweeper-car, the combination with a car-base, of hangers secured to the opposite sides of the bottom of the car, each consisting of a bracket and a link removably bolted at its upper and lower ends to the bracket, the adjacent faces of the bracket and link being curved on the arc of a circle to form a segmental slot, bearings vertically movable 115 in said slots, a brush-shaft journaled in said bearings, means for raising and lowering the bearings, and means for driving the brush-shaft, substantially as described.

WILLIAM A. MC GUIRE.
ELMER E. COOK.
